UNITED STATES PATENT OFFICE.

GEORGE WELSBY SCOTT, OF CHICAGO, ILLINOIS

CAR CONSTRUCTION.

No. 859,896.

Specification of Letters Patent.

Patented July 9, 1907.

Application filed March 24, 1903. Renewed February 7, 1907. Serial No. 356,259.

To all whom it may concern:

Be it known that I, GEORGE WELSBY SCOTT, a citizen of the United States, residing at Chicago, in the county of Cook and State of Illinois, have invented certain 5 new and useful Improvements in Car Construction, of which the following is a specification.

My invention relates to the railway cars used for carrying liquids in tanks, and particularly to the underframing for supporting the said tanks the same being 10 preferably a rigid structure, made of metal. In my Patent No. 740,187, issued September 29, 1903, I have shown the general form of underframing which I prefer, and in another co-pending application by myself and Paul Carpenter, No. 132,309, I have shown the application 15 of said framing to the support of the tanks commonly in use for carrying liquids. The present invention has for its object to improve the rigidity, compactness and efficiency of those structures and to make the frame more simple and stronger in its design. Other 20 objects of my invention are to provide for a fixed tank support upon a rigid frame so that all strains are transferred along the center supporting beam of the frame; to make easy and ready the assembling of the parts of the frame; to provide in improved bolster member in 25 the frame, to decrease the number of parts and generally to improve the structure for its purpose.

I attain these objects and other advantages as will hereinafter appear, by means of the construction and assemblage of parts as illustrated in preferred form in 30 the accompanying drawings, wherein,—

Figure 1 is a perspective view of one end of my tank car frame.

Figure 2 is a front elevation of the body bolster.

Figure 3 is a plan view of the same.

35 Figure 4 is a central vertical section of the body bolster, and Figure 5 is a detached view of the center pin for the bolster.

Figure 6 is a side elevation of one of the tank bolsters.

Figure 7 is a plan view, and Figure 8 is an end view 40 of the same.

Figure 9 is a central vertical section of the tank head-block and bracket, and Figure 10 is a front elevation of the same.

Figure 11 is a fragmentary horizontal section through 45 one of the outside ends and the bolts holding the block and bracket together.

Figure 12 is a plan view of the tank head-block and bracket.

The common practice at the present time in tank 50 car construction is to employ a series of wedges or supporting blocks placed upon the side of the tank and on the floor of the car and held in place by spikes or bolts; in metallic car construction the prevailing custom is to support the tank from rolling sidewise by means 55 of separate wedge bolsters on the floor, or sometimes struts extended from the side sills of a flat surrounding

frame. In all these the blocks placed under the tank to prevent it from rolling are separate pieces, not parts of the frame, and in most cases there is an additional bolster placed underneath the frame of the car to co-operate with the truck bolster, which is a member 60 separate from the members of the car frame. The great disadvantage of all constructions at present known to me is that they are composed of parts which are put together in such a way that by the constant jarring of 65 the tank upon its supports they become loose and eventually tear apart, and tend to destroy the entire structure.

To overcome these disadvantages and others, and to provide a structure at once eminently suitable for its 70 purpose and rigid and substantial in character and having a reduced cost of construction, I have employed in the first place a frame in which the end thrusts of the tank in case of shock are taken directly upon a single stiff member which runs from end to end under the 75 center of the tank. In the second place I provide a bolster for the ends of the tank which itself forms a body bolster of the frame, a floor beam, and a tank bolster in one, and is rigidly connected with the said center sill or beam. I also use tank bolsters which while 80 they perform the functions of the ordinary chock blocks under the sides of the tank, also constitute members of the frame of the car, connecting the sills. For the end supports of the car I provide a bracket and head-block, which latter is held in place adjustably 85 and the bracket attached immediately to the direct-line thrust and tension member under the center of the tank.

In the accompanying drawings, the general form of the frame, comprising the side sills 13 and the center 90 sill 14 with the diagonal braces 20 and 21, is essentially the same as in the applications above referred to. Near the ends of the frame, at points opposite to the position of the truck bolster, I provide the frame with a member 15 which forms at the same time a body bolster and one of the elements of the car framing. It is in 95 one rigid piece and extends between the side sills and is joined to the center sill 14 by head abutment of the latter and riveting with angle irons. Between this bolster and the end sill 27 are the usual draft sills 19, rigidly attached in any desired manner to both the 100 bolster 15 and the end sill 27, the whole being stiffened by the addition of the top plate 26.

The body bolster 15, as shown in Figures 2, 3 and 4, is made in a general truss form and has integrally with 105 it a recessed seating face 16 for the reception of the tank, its two ends being somewhat coped and generally preferred to fit within the channel bars forming the side sills 13. The beam may be made with extra stiffening flanges 17 as shown in Figure 1. At the center, on the 110 under side of the body bolster is provided a bearing plate 34 shown in section in Figure 4, which is provided

with an opening 36 and a headway 35 is cut out of the web of the member 15 for the reception of the center pin or bolt 37. It will be understood that this bolt 37 is placed within the opening 36 and then provided 5 with a collar 38 which may be pinned in place. The bolster is provided with top and bottom flange members, after the manner of an I-beam and preferably the center sill and the draft sills, (14, 19), rest upon the lower flange of this bolster. It being understood that 10 the members 15 serve the purposes of body bolsters and take the entire weight of the frame and of the car, and contents if any, and transmit it directly to the truck bolsters below. The bolster may be provided also with the bearings 18 to co-operate with the side 15 bearings of the truck.

Intermediate between the body bolsters in the frame I provide a series of tank bolsters 22, which are preferably made in half sections and abut against the center sill 14 as will be plain from Figure 1. They are in 20 general form the same shape as the half of the body bolster except that they may be conveniently made without the vertical stiffening ribs 17. They are also provided with curved recessed seats 23 to take the form of round tanks ordinarily used on railway cars. 25 Though I preferably use a single center sill 14 it will be evident that two or more can be used in the same way.

The bolsters thus serve the purpose of floor beams, and bolsters or chock blocks under the side of the tank, 30 and connections between the side sills of the frame; and in addition to this the bolster 15 forms a car bolster to co-operate with the truck bolster.

In order to take the end thrusts of the tank which are induced by the shocks of starting and stopping and 35 also by the hammer like blow of the surging liquid inside the tank, I provide, preferably upon the draft sills 19 a bracket 24 which is provided with a supplementary movable head-block 25 attached thereto, by a series of screws tapped through the bracket, both 40 said parts resting upon the sills 19 and the bracket 24 preferably also abutting against the top plate 26 for additional stiffness. The head-block for the tank is illustrated in section in Figures 9 and 10 where it will be seen that it is formed with a recess on its inner side 45 for taking a wooden or other filling or cushion block 28 for immediate contact with the tank. The head-block 25 is thrust securely and tightly against the tank by means of the screws 29 which may be fixed in place by the usual nut-lock. The head of the two outer 50 bolts 29 may be provided with annular grooves as shown in Figure 11 and a pin 31 is provided which co-operates with said grooves to allow the nut to turn, while yet retaining it in place within the head-block 25.

From the above description it will be seen that I 55 have provided a tank car frame in which the end portions of the tank are supported upon integral rigid recessed beams which at the same time form integral members for the car frame, also body bolsters for the same and that these two beams at the end portions of 60 the tank are rigidly connected together by a single longitudinal beam and this latter is connected by means of the diagonal braces to the side sills of the frame. The thrust on the ends of the tank being taken up by the brackets and head-blocks 24, 25, fixed on 65 the draft sills, and these latter being directly fixed to

this continuous center element of the frame and strapped to the side sills also, it will be evident that any lengthwise thrusting strain upon the tank will be communicated to all three of the longitudinal members and that the end thrust will immediately be taken up 70 by the brackets attached to the single central beam. At the same time the position of the tank upon the frame is secured in curved recessed bearing faces 16, of the bolsters which are rigid and not composed of parts which may work loose and come apart as in the ordinary construction. It may also be seen that in this construction the weight of the tank and its contents is borne directly by integral members of the car framing; the individual loads or stresses then being transmitted in the most direct manner and with a minimum of 80 straining effect to the body bolsters, where they are then transmitted to the truck bolsters below. The many advantages of this construction will readily occur to those familiar with the art.

The bolsters may conveniently be made by casting, 85 in the form shown. By this means they may be made more uniform in weight and dimensions and very much facilitate the assemblage of parts in making car frames. In this way also the bearing plates under the bolsters, and the openings for the center pin may be 90 provided. While I have illustrated and described this construction as especially adapted to car frames used for tank cars, it will of course be understood that the invention is equally applicable to any other car frame. The advantages of using an integral member to form 95 the cross beam of the frame and the car bolster at the same time are plainly as valuable in one kind of frame as another, and are not limited to frames wherein the bolster is made with a recessed top to accommodate a tank placed thereon. Also the advantages of forming 100 the bolster with vertical ribs to strengthen it against longitudinal shocks from the center sill, and the depressed position of the lower flange, by which the center sill is given an additional support independent of the riveted angle irons, are entirely independent of the 105 particular use of this construction for tank car frames.

Having thus described my invention and illustrated its use, what I claim and desire to secure by Letters Patent is the following:

1. A tank car frame comprising a central longitudinal sill and two recessed cross beams for the reception of the tank rigidly attached thereto forming at the same time body bolsters and members of said frame. 110
2. In an underframe for tank cars, in combination with the longitudinal center sill thereof, the combination body bolster and cross beam comprising a single member directly attached to the side sills and abutting against the end of the center sill and being provided with a recessed top for the reception of the tank, substantially as described. 115
3. In a metallic underframe for tank cars, a body bolster having a recessed top portion for the reception of the tank, a flat portion to serve as a floor beam, and the whole bolster forming an integral member of the frame of a car. 120
4. In a metallic underframe for tank cars a body bolster provided with a recessed top portion for the tank, a floor portion, and a bearing plate to co-operate with the truck bolster, and provided with means for receiving and retaining the center pin of the truck. 125
5. In a metallic underframe for tank cars, in combination with a central longitudinal sill, an integral recessed tank bolster forming at the same time a member of the frame and abutting against said center sill, draft sills extending in the same horizontal plane with said center sill, and a thrust bracket and head-block for the tank rigidly secured to said draft sills, substantially as described. 130
- 135

6. In a metallic underframe for tank cars, a body bolster integrally formed of a generally I-beam shape, having a horizontal flat portion for the floor planks and a recessed top portion to receive the tank, and being provided underneath with a bearing plate and a recess for the reception of the center bolt of the car truck. 25
7. In a metallic underframe for tank cars, in combination with a single center sill thereof and a body bolster provided with an integral recessed top, of draft sills extending in the same horizontal plane with the center sill and an adjustable abutment thereon for the end portions of the tank, substantially as described. 10
8. In a metallic underframe for tank cars, in combination with a single rigid longitudinal member of said frame, a bracket fixed upon an extension of said longitudinal member, a movable head-block for the tank resting on said extension and a set of bolts threaded into said brackets and rotatably retained in said head-block, whereby the head-block may be adjusted in longitudinal position along said extension, substantially as described. 15
9. In a metallic underframe for tank cars, a body bolster provided with a floor portion and a recessed portion for the
- tank, a bearing plate to co-operate with the truck bolster, means for retaining the center bolt therein and bearings at each side of said center plate, whereby said body bolster performs at the same time the functions of a cross beam of the frame in addition to that of a body bolster to support the weight of the tank upon the truck, substantially as described. 25
10. In a metallic underframe for tank cars, a member comprising a recessed upper face for the reception of the tank, with wings extending therefrom attached to the side sills of the frame and an integrally formed bearing plate to co-operate with the truck bolster whereby the tank bolster, the cross beam and the frame bolster and the bearing plate constitute an integral piece and transmit the weight of the tank immediately to the truck bolster, substantially as described. 35

In testimony whereof I have hereunder signed my name in the presence of the two subscribed witnesses.

GEORGE WELSBY SCOTT.
